(57) **CLAIM**

The ornamental design for a sun shading system accessory as shown and described.

DESCRIPTION

FIG. 1 is a front perspective view of a first embodiment of a sun shading system accessory including first and second assembled components of the present invention showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view of an embodiment of a first component of a sun shading system accessory of the present invention showing our new design;

FIG. 9 is a front view thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a front perspective view of an embodiment of a second component of a sun shading system accessory of the present invention showing our new design;

FIG. 16 is a front view thereof;

FIG. 17 is a rear view thereof;

FIG. 18 is a right side view thereof;

FIG. 19 is a left side view thereof;

FIG. 20 is a top view thereof;

FIG. 21 is a bottom view thereof;

FIG. 22 is a front perspective view of a second embodiment of a sun shading system accessory including first and second assembled components of the present invention showing our new design;

FIG. 23 is a front view thereof;

(Continued)

FIG. 24 is a rear view thereof;
 FIG. 25 is a right side view thereof;
 FIG. 26 is a left side view thereof;
 FIG. 27 is a top view thereof; and,
 FIG. 28 is a bottom view thereof.

The dashed lines in the drawings are for the purpose of illustrating portions of the sun shading system accessory, which form no part of the claimed design. The dot dashed lines in the drawings define the bounds of the sun shading system accessory and form no part thereof.
